Primary Examiner — Llorellys Martinez-Rivera(74) *Attorney, Agent, or Firm* — INNOVATION
CAPITAL LAW GROUP, LLP; Vic Lin(57) **CLAIM**

The ornamental design for a vehicle shelving extrusion as shown and described.

DESCRIPTION

FIG. 1 is a perspective view of a vehicle shelving extrusion, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The vehicle shelving extrusion is shown with a symbolic break in its length. The appearance of any portion of the vehicle shelving extrusion between the break lines forms no part of the claimed design.
